BOX

Clarence H. Walker, San Mateo, Calif.

Application November 19, 1934, Serial No. 753,711

2 Claims. (Cl. 229—43)

This invention relates to improvements in boxes and more particularly to fiber boxes for shipping and the method of shipping perishables.

Among the objects of the invention is to produce a thermo-insulating box of conventional material that will prevent the interchange of interior and exterior atmosphere.

Another object is to produce such a box without materially adding to the cost of conventional shipping boxes of the same capacity.

A further object is to stiffen the open edge of the box to prevent it springing away from the telescoping flange of the cover.

Other objects and advantages will appear as the description progresses.

In this specification and the accompanying drawing, the invention is disclosed in its preferred forms. It is to be understood, however, that it is not limited to these forms because it may be embodied in other forms within the purview of the claims following the description.

The present disclosure relates particularly to the shipment of perishables such as natural flowers. The cars for such shipments are provided with compartments containing ice over or through which a forced draft of air is directed by the ventilating system. The danger in any suitable system of transportation is not the refrigerated or maintained temperature, but it occurs when the boxes are withdrawn or subjected to either a rise or a drop in temperature in the interior of the boxes. To overcome this effect, it has been the practice heretofore to wrap the flowers carefully in paper before boxing and then to wrap the boxes with an outer layer of paper. These precautions consume extra time and material besides adding to the weight that must be paid for at express rates and reduces the quantity of profitable commodity that can be carried in a given carrier space.

Another method is to refrigerate each box separately with ice, or "dry ice", which requires even greater care in wrapping to exclude air circulation through the boxes to avoid excessive dissipation of the cooling element and evaporation of the flower moisture by the exchange of interior and exterior atmosphere.

In the one sheet of drawings:

Fig. 1 is a perspective view from above looking into an open box constructed in accordance with this invention.

Fig. 2 is an enlarged fragmentary detail of a corner of the box before the sealing flanges are bent inward.

Fig. 3 is a vertical section of the upper portion of the box with the cover thereon.

Fig. 4 is an enlarged fragmentary detail in vertical section of a modification in which the sealing flange forms an integral part of the cover.

Fig. 5 is a similar view in which the sealing flange on the box is bent outward to engage the flange of the cover.

Fig. 6 is a similar view in which the sealing flange is applied to the under side of the cover parallel with the outer flange on the cover to form a channel to receive the unflanged edge of the box.

Fig. 7 is a similar view showing a greatly enlarged detail of the structure of the cellular board preferably used in the structure of the box.

In detail, the construction illustrated in the drawing, referring to Fig. 7, comprises the inner and outer sheets of fiber board 1—2 enclosing the corrugated core 3 of similar material all glued together to form a laminated assembly. This material and the basic structure of the box are conventional except as improved by the present invention.

The box is preferably formed from a single sheet of cellular fiber board blanked to form the bottom 4 with the integral sides and ends 5—5 and 6—6 respectively. The ends have the integral tabs 7—7 formed thereon. The outline of the bottom 4 and the tabs are indented or scored to facilitate bending when the box is set up. The tabs fold inward and are joined to the adjacent ends of the sides 5—5 by gluing or by the clinched staples 8—8. This forms the conventional rectangular box.

The sides and ends have the upwardly extended sealing flanges 5' and 6' integral therewith and bendable at the score lines 9—10 and cut away at 11—12 to form miter joints at 13 when the sealing flanges are folded inward as in Fig. 1.

When the flanges 5'—6' are flexed inwardly on the indented score lines at 9—10, the opposed portions of the walls form cushions which urge the flanges upward as in Figs. 1 and 2, see also Fig. 7.

The conventional cover comprises the top 14 with the down-turned flange 15 adapted to telescope over the upper margins of the sides and ends 5—6. The cover end flanges also have integral tabs 15' to join the end flanges to the side flanges 15 to form a flange entirely encircling the top of the box in the usual manner. It is preferable to fold the tabs 7—7 inward and the cover tabs 15' outward to form smooth meeting

surfaces between the cover flange 15 and the walls of the box to insure a snug frictional fit.

When the cover 14 is pressed down on the box, the inclined sealing flanges 5'-5' and 6'-6' engage the under side of the cover and are forced downward against their normal urge upward as previously described. The sealing flanges present the sharp edges 16 to the plane of the cover which insures a continuous line contact therewith flexible enough to conform to normal distortions in the plane of the cover 14 and insure a sufficiently airtight seal therewith when the box is roped. It has been demonstrated that such a box will withstand pressures above atmosphere. It is not the intention to make an airtight box but to seal the box against exchange of interior and exterior air due to drafts, air blasts, expansive and contractive changes in temperature or thermosyphonic action.

20 In the modification shown in Fig. 4, the flange 54 is bent outward to seal against the flange 15 when the cover is pressed down. In this instance, the corners of the flanges are not mitered as at 11-12 but abut each other at the corners.

25 The modification in Fig. 5 is a simple reversal of parts with the same result. The flange 55 is integral with the flange 15 and is folded inward and sealed against the sides and ends of the box.

Fig. 5 is a further modification in which the 30 flange 56 is glued or otherwise fixed to the cover 14 to form a channel with the flange 15 to enclose the unflanged edge of the box. This type of seal is more expensive to produce but has certain advantages, especially in boxes of larger capacities 35 since the seal is more positive and adds to the stability of the upper portion of the box.

The form shown in Fig. 1 is preferred because of its simplicity, ease of production and manipulation and the further fact that the mitered corners of the flanges 5'-6' form an internal reinforcing frame for the upper portion of the box.

5 In extreme cases where additional sealing is desirable, the upper surfaces of the flanges 5'-6' can be coated with cotton lint, felt or other "fuzzy" material.

This improved box is packed and tied with rope or twine in the usual manner but requires no 10 external wrapping. The cellule space incidental to the corrugated core 3 creates a thermo-insulating wall due to the dead air space.

Having thus described this invention, what is 15 claimed and desired to secure by Letters Patent is:

1. A box having a cover, the walls of said box being internally scored adjacent the upper edges, the flange being cut away at the corners of the 20 box and forming meeting ends adapted to normally hold the flange inclined at an angle to the under plane of said cover and forming a continuous line contact therewith.

2. A box and a cover therefor having inner and 25 outer interspaced sheets adapted to form air insulated enclosing composite walls; an inclined flange encircling the upper edge of the box and having only a corner of its edge in contact with the under plane of said cover, the cut angle of 30 said flange at the corners being arranged to maintain the angular inclination of said flange with respect to said cover.
